(57) **CLAIM**

The ornamental design for a wrist-watch with reversible body, as shown and described.

DESCRIPTION

FIG. 1 is a perspective view of a wrist-watch with reversible body, showing my new design;

FIG. 2 is a front perspective view of a wrist-watch with reversible body, shown with the watch portion rotated inward to reveal the rear cover facing outward;

FIG. 3 is a left side elevational view thereof, the right side being a mirror image thereof;

FIG. 4 is a front elevational view thereof, the rear view being a mirror image thereof;

FIG. 5 is a top plan view thereof, shown with the watch facing outward;

FIG. 6 is an alternate top plan view thereof, shown with the watch portion rotated inward to reveal the rear cover facing outward; and,

FIG. 7 is a perspective view of the wrist-watch with reversible body.

The broken line showing of bands and dials are environmental only and form no part of the claimed design.
